JACOB T. LANDGRAF AND ROY G. MILLER, OF ROCKFORD, ILLINOIS, ASSIGNEES TO J. W. MILLER CO., OF ROCKFORD, ILLINOIS, A CORPORATION OF ILLINOIS

BROODER HEATER

Application filed December 9, 1929. Serial No. 412,586.

Our invention relates to heaters of the kind adapted to be employed in brooders or the like, wherein an oil heater of the type arranged to have the flame thereof regulated by 5 regulating the height of oil around the wick is desirable.

These heaters have, in the past, consisted essentially of a supply container adapted to hold the main supply of oil and a burner and 10 means for conducting the oil from the supply container to the burner. A reservoir or the like is maintained at the bottom of the burner, and the wick is permitted to dip into the oil in this reservoir, the height of the flame de- 15 pending upon the height of the oil upon the wick. The most common way of regulating the height of oil on the wick has been to raise and lower either the burner or the supply container, thereby altering the oil level. Vari- 20 ous attempts have been made to do this automatically, a thermostat or similar device being provided to mechanically raise or lower one of these two members. It will be seen that in order to make this device practical for 25 brooders and the like the equipment employed must be relatively cheap and easy to manu- 30 facture. In most cases it has consisted merely of a series of levers operated by wafers which expand when the temperature increases and contract when the temperature decreases. 35 However, since this wafer must lift either the burner or a tank filled with oil, it operates against a relatively large load and the sensitivity of the wafer is thereby reduced. In 40 addition, the joints of the machine tend to clog up under the use to which it is put and become hard to operate, thereby further in- 45 creasing the load upon the wafers. Furthermore, when the burner is moved up and down, unless very well guided, it has a tendency to lift side wise and burn in a tilted position, thereby producing an uneven flame. On the other hand, if the burner is well guided, consider- 50 able friction is developed between the guide and burner and the load on the wafers is again increased. These, among other things, have caused the burners of this type to be considered highly unsatisfactory.

In some instances, the oil container and 55 burner have been maintained in fixed posi-

tions, the oil storage being held at a point slightly above the burner, and a needle valve has been positioned at the outlet of the container, the needle valve being regulated by some suitable type of thermostat. In order, 55 however, to provide sufficiently delicate regulation, the orifice of the needle valve must be very small, thereby being easily clogged. The tendency toward clogging is so serious in this field as to render this type of little 60 practical use. It has further been observed that in cold weather when the viscosity of the oil increases, it does not flow readily through a small orifice, and this tends to make the regulation of the burner uncertain. 65

Another serious objection to automatic machines of this character is the danger from fire due to the flooding of the burner. So far as I am aware, none of the machines of the prior art have provided means for positively 70 preventing the flooding of the burner. Another serious objection to the machines of the prior art is the fact that should the weather become warm and the automatic devices shut off the supply of oil so that the burner goes 75 out, no means are provided for automatically relighting the burner should the weather again become cold and the oil supply be renewed. When this occurs with the burners now known, the oil merely flows into the 80 burner and overflows the burner dissipating the oil which flows during this period.

We have, therefore, aimed to provide a burner wherein the level of the oil supplied to the burner may be maintained within 85 limits and varied automatically, to regulate the height of flame in the burner.

Another object of our invention is to provide a thermostatically controlled brooder heater of greater accuracy and safety than 90 those heretofore known.

We have further aimed to provide a brooder heater in which the oil container, the burner and the conduits are fixed in position and wherein automatic means are provided 95 for maintaining a suitable oil level in the burner.

Another object of the invention is the provision of a burner wick adapted to maintain a pilot flame when the automatic regulation 100

permits the oil level to drop below the operating level of the burner.

We further aimed to provide means for preventing the burner from flooding if the flame thereof goes out or the flow of oil becomes too rapid.

Other objects and attendant advantages will become apparent to those skilled in the art from the following description and the accompanying drawings, in which—

Fig. 1 is a side elevation of a brooder incorporating our improvements, the canopy and screen being shown in section;

Fig. 2 is a fragmentary, longitudinal section through our improved brooder heater;

Fig. 3 is a section on the line 3—3 of Fig. 2, and

Fig. 4 is a perspective of the wick employed in our improved brooder heater.

The heater consists in a general way of an oil storage tank, indicated generally by the numeral 5, an oil control chamber, indicated generally by 6, a burner, indicated generally by 7, arranged to receive oil from the oil control chamber 6 and provide a heating flame, and means for conducting the oil between these three members. A base, which may be of any suitable construction and design but is here shown to be formed of sheet metal, is indicated by the numeral 8 and serves to support the assembled mechanism. The oil supply chamber 6 is provided with means for automatically maintaining a constant oil level therein and for automatically altering this level in order to provide a uniform air temperature about the chamber as will presently appear more fully.

Referring now more particularly to the oil storage tank 5, we have provided a cylindrical tank having an open top arranged to receive a closure 9 having a handle 10 to facilitate its use. In order that substantially all of the oil in the container be available for use to the burner, we have arranged to elevate the tank as shown in Fig. 2. The side walls 11 of the tank are caused to extend downward to form a supporting base for the tank upon the platform 8. The bottom 12 of the tank is positioned on the inner side of the side walls 11 at a height equal to or greater than the maximum height of the oil in the base of the burner, so that substantially all of the oil will flow therefrom by gravity. An oil supply pipe 13 is positioned in the bottom 12 of the tank 5 and caused to project slightly above the bottom, as indicated at 14, whereby any dirt or refuse which may have settled from the oil to the bottom of the container will be prevented from entering the pipe with the oil. The oil supply pipe 13 is provided with a threaded end 15 engageable with an opening in the bottom of the oil control chamber 6.

The burner 7 is supported on the opposite end of the base 8 and is connected with the

oil control chamber 6 through a horizontal pipe 16 and vertical pipes 17 and 18 connected thereto. The pipes 17 and 18 also serve to support the burner 7 upon the supply pipe 16. The supply pipe 16 is provided on its outer end with a cap 19 threaded thereon to permit its removal for the purpose of draining the system. A burner base 20, cylindrical in shape, and having a cylindrical wick 21 shown in detail in Fig. 4 and presently to be described, is positioned on the upper end of the pipes 17 and 18 and has communication therewith to permit oil to enter the base from the pipe. The burner base 20 is formed of two concentric cylinders 22 and 23 closed at the bottom except for the openings to receive the pipes 17 and 18 and open at the top, the upper edges of the cylinders being flared, as shown at 24 and 25 to receive the burner chimney, presently to be discussed. The burner chimney consists of three concentric, metallic cylinders 26, 27 and 28 held in position by tie rods 29 and 30 passing diametrically therethrough. The two inner cylinders 27 and 28 form the burner plate and are highly perforated, their lower edges resting in the flared portions 24 and 25 of the burner base 20. These plates are adapted to be heated by the burning of the oil on the wick 21. The outer cylinder 26, which serves as a circulating drum for the heat generated by the flame, is provided at its lower end with a rim 31 projecting inward provided with perforations 32 through which air may enter to the burner. Upper flange 33 projecting diagonally inward serves to increase the velocity of the emerging heated air.

The burner wick 21, shown in detail in Fig. 4, is of the usual conventional material and consists of asbestos web fabric having wire interwoven therewith to lend the structure rigidity and strength. It has been observed in the operation of heaters of this character that carbonization of the wick occurs near the base of the flame. In this manner, carbon and heavy tarry substances are deposited in the pores of the wick rendering it almost impervious to oil whereby the supply of oil to the flame is reduced and the operation of the burner impaired. We have found that if the burner wick is periodically inverted so that the recently burned portion of the wick is inserted downward into the oils, the wick will become softened and again pervious to the oil.

It will be observed that in order for the wick to burn, it is necessary that the level of the oil be within the base 20 of the burner. However, in the operation of an automatically controlled burner of this character the external temperature often becomes such as to cause the supply of oil to be completely shut off. When this occurs, the wick will burn until the oil level is reduced to a point where the wick no longer has contact with

the oil and will ordinarily then be extinguished. Under ordinary circumstances if the surrounding temperature should again go down the supply of oil will be renewed but 5 the flame, having gone out, will not be renewed unless special means are provided for this purpose. In order to prevent the flame on the wick from being completely extinguished, we have provided a pilot wick, indicated generally by the numeral 34. Examination of Fig. 4 will show that this wick is pivoted at the center of the main wick 21, which permits the pilot wick to project outward on either end of the burner wick cylinder. The pilot wick 34 is adapted to extend downward through one of the pipes 17 or 18 into the horizontal supply pipe 16 whereby, after the oil level drops below the base of the burner, a small quantity of oil will be provided to the wick 21 by means of the pilot wick 34, which will be sufficient to maintain a small flame within the burner. The pilot wick 34 having a pivotal connection 35 with the main wick 21, may be reversed from side 25 to side when the wick 21 is inverted in the base of the burner 20.

It should be observed that in burners of this character the intensity of the flame is regulated by the position of the oil along the 30 surface of the wick. When the oil is high, the wick has an intense flame, and when the oil is low the wick has a weaker flame. Thus, the intensity of the flame and the amount of heat emitted by the burner 7 may be regulated 35 by regulating the lever of the oil in the burner base 20. In order to so regulate the oil level we have provided the oil control chamber 6, to which the burner 7 and the oil supply tank 5 are attached by means of oil supply lines 16 and 13, respectively.

The oil control chamber 6 is positioned between the oil supply container 5 and the burner 7 in such a manner that the oil leaving the container 5 must first pass into the control 45 chamber 6 and then through the supply pipe 16 to the burner 7. While this chamber may be made in innumerable shapes and sizes, we have here shown it attached to the base 8 and having a chamber formed by circular side 50 walls 37, a U-shaped projection 37a thereof forming a valve chamber 38. Reference to Fig. 2 will show an outlet needle valve 39 secured in the bottom of the valve chamber 38, having an orifice 40 vertically positioned therein. The bottom end 41 of the valve is threaded for engagement with a threaded opening 42 in the bottom of the valve chamber 38. The opening 42 connects with a passage 55 way 43 cast in the bottom of the oil control chamber 6. The outer end of the passage way 43 is threaded to receive the threaded end 44 of the oil pipe 16. A lateral hole 45 through the valve 39, intersecting the orifice 40, permits the oil to enter the orifice from 60 the chamber 38, pass through the orifice into

the passageway 43, and from there into the oil supply pipe 16. A valve lever 46 is threaded near its lower end 47 into the valve 39 and is arranged to close the orifice 40 when turned downward so that its lower end engages the valve seat 48. This valve serves merely as a small outlet connecting the oil control chamber with the supply pipe 16 and is normally adapted to be either fully opened or fully closed, though clearly a certain amount of regulation may be had at this point if desired. An inlet valve 49, almost identical in shape and size with the outlet valve 39, is positioned in the bottom of the valve chamber, whereby its orifice 50 connects with a passage way 51 arranged to receive oil from the supply pipe 13. We have found it advisable to have the orifice 50 somewhat smaller than the orifice 40 of the outlet valve whereby the amount of oil entering the chamber at this point may be more closely regulated. It will be seen that, here too, we have provided a lateral hole 52 in the inlet valve corresponding to the lateral hole 45 in the outlet valve to permit oil to pass from the orifice 50 into the chamber 38. A valve stem 53 is slidably positioned in the valve 49 to move vertically upward in opening the valve and vertically downward against the seat 54 to close the valve. It will be seen that the bottom of the float chamber 36 is somewhat lower than the bottom of the valve chamber 38 and of the lateral hole in the valves 45 and 52 are somewhat spaced from the bottom. This is to permit the sediment from the oil to drop into the bottom of the float chamber 36 and prevent it from being carried into the valve and stopping up the orifices.

It will be seen that when the valves 46 and 53 are opened, oil will enter the control chamber 6 from the supply container 5 through the orifice 50 and leave the control chamber 6 for the burner 7 through the orifice 40. The orifices 40 and 50 are of such size as to permit a greater quantity of oil to flow therethrough than is consumed by the burner. As oil enters the control chamber and begins to fill this, the orifice 40 being larger than the orifice 50, the oil will quickly flow into the burner to approximately the same level, and as oil continues to flow, the level in the two will remain the same, gradually moving upward. We have provided means for automatically closing the orifice 50 when the level reaches a desired point and means for again opening the orifice 50 to permit the entrance into the chamber 6 of an appropriate amount of oil when the burner 7 has consumed sufficient oil to materially lower the level. We have also provided means for raising or lowering this level, thereby raising or lowering the flame in the burner to maintain a constant temperature in the region immediately surrounding the burner.

In order to maintain a constant level of oil in the chamber 6 and the burner base 20, we have provided a float 55 arranged to rest in the float chamber 36 and be raised and lowered by the oil. A horizontal lever 56 is fixedly attached to the float 55 and pivotally attached to the top of the valve stem 53 at 57. The horizontal lever 56 is also pivotally attached near its mid-point to a supporting pin 58 presently to be described. Referring to Fig. 2, it will be seen that the float and inlet valve are shown in the closed position with the oil at a desired level.

Let us now assume that the burner 7 has consumed sufficient oil to lower the oil level a small amount. The float 55 will be lowered raising the valve stem 53 and permitting oil to enter through the orifice 50. When the oil level goes up the float 55 will be raised, lowering the valve stem 53 and closing the orifice 50 when the oil level reaches its previous point. In this way the oil level is maintained at substantially a constant point. However, such an arrangement would permit only a constant flame in the burner 7. In order to regulate the height of the flame in the burner and consequently the heat emitted thereby, we have provided means for automatically raising or lowering the float support pin 58. The pin 58 is supported from a bracket 59 lying crosswise of the float chamber 36 and secured to the side walls thereof by means of screws 60. A collar 61 projects upward from the center of the cross-piece 59 and serves as a sleeve for guiding the movement of the pin 58 which is permitted free sliding endwise movement in the collar 61. The upper end of the pin 58 is provided with an annular shoulder 62 against which a spring 63 may bear, the spring 63 acting between the shoulder 62 and the upper edge of the sleeve 61 to normally urge the pin 58 upward. It will be seen that the normal tendency of this spring is to hold the float 55 at its highest point and consequently maintain the oil level in the control chamber fixed at its highest point. A U-shaped bracket 64 is positioned on the sleeve 61 by means of the screw 65. The other end of the bracket 65 is provided with an advancing screw 66 having a knurled head 67, the lower end of the screw being fixedly attached to a wafer thermostat indicated generally by the numeral 68. The wafer is positioned between the ends of the bracket, the lower side of the thermostat 68 is adapted to bear against the upper end of the pin 58, forward movement of the screw 66 urging the thermostat 68 downward and forcing the pin 58 downward 60 against the pressure of the spring 63. An overflow pipe 69 is positioned in the side walls 37 of the float chamber so that should the valve stem 53 be prevented from seating and the oil continue to flow into the chamber 65 it may be permitted to flow out through the

overflow pipe 69, which will conduct it to a point of safety, thereby preventing the burner from overflowing and catching fire.

Referring to Fig. 1, it will be seen that the burner, among other things, is adapted to be employed with a chicken brooder having a screen indicated generally by 70, for the purpose of preventing the chickens from coming in contact with the burner 7. A conical canopy 71 having supporting legs 72 is adapted to be centrally positioned over the burner 7. The canopy projects outward sufficiently to cover the oil control chamber 6 and serves to enclose the heat from the burner 7 and reflect it downward against the ground. It will be seen that the thermostat 68 is positioned close up under the side of the canopy 74 wherein it will be protected from mechanical injury by the chickens under the canopy. In addition it is so positioned as to be within the stream of downwardly moving warm air along the sides of the canopy 71 which tends to prevent sudden changes of temperature about the thermostat. The operation of the heater will be seen to be at once simple and convenient. In starting the heater the screw 66 is drawn upward until the thermostat 68 is out of contact with the pin 58 permitting it to assume its highest position. The valve 39 is then opened and oil is permitted to flow into the base 20 of the burner 7, saturating the wick 21. The burner is then lighted and will burn at its maximum intensity, at which point it is permitted to operate until the temperature of the air under the canopy 71 has reached the desired point. When this has occurred the thermostat 68 is moved downward until it comes in contact with the upper end of the pin 58. The thermostat 68 is now regulated by screwing it downward until the temperature of the air under the canopy 71 no longer increases or until this temperature becomes constant. This moving downward of the thermostat 68 forces the pin 58 downward and with it the float 55 thus lowering the level of the oil in the control chamber 6 and in the base 20 of the burner 7. When the point has been reached where the air under the canopy remains approximately constant in temperature, manual regulation of the thermostat is stopped. It will be seen that small variation of temperature under the canopy 71 will be cared for by expansion and contraction of the thermostat 68, expansion of the thermostat causing the float 55 to be forced downward, thus lowering the level of the oil in the burner base 20 and decreasing the intensity of the flame. Contraction of the disc 68 causes the pin 58 to be raised, raising the level of the oil and increasing the temperature of the flame.

It will be seen that the resistance to the action of the thermostat 68 is very small and consequently the regulation of the burner will be relatively accurate. In like manner

it will be seen that the only moving parts in the heater are those directly concerned with the actuation of the valve 49, and that all of these parts are relatively well protected and consequently have small tendency to jam.

While we have thus described and illustrated a specific embodiment of our invention, we are aware that numerous alterations and changes may be made therein without departing from the spirit of the invention, and we do not wish to be limited except as required by the prior art and the scope of the appended claims, in which—

15 We claim:

1. In combination, a burner, a fuel supply connected for gravity feed thereto, a fuel control chamber in the connection controlling the oil level in the burner, said chamber having an inlet and an outlet, a float valve structure controlling the chamber inlet, and heat responsive means connected to said float valve structure to vary the burner oil level to maintain the surrounding atmosphere at a constant temperature.

2. In combination, a burner, a fuel supply connected for gravity feed thereto, a fuel control chamber in the connection for controlling the oil level in the burner, said chamber having an inlet and an outlet, a float valve structure controlling the chamber inlet and heat responsive means connected to said float valve structure mounted on the exterior of said control chamber and connected to said 35 float valve structure to vertically shift the same to vary the burner oil level to maintain the surrounding atmosphere at a constant temperature.

3. In combination, a burner, a fuel supply connected for gravity feed thereto, a fuel control chamber in the connection for controlling the oil level in the burner, said chamber having an inlet and an outlet, a vertically movable needle valve controlling the chamber inlet, a float having a horizontally disposed arm pivotally connected to said needle valve, and heat responsive means for supporting said arm to vary the vertical position thereof, to determine the burner oil level 50 and maintain the surrounding atmosphere at a constant temperature.

4. In combination, a burner, a fuel supply connected for gravity feed thereto, a fuel control chamber in the connection for controlling the oil level in the burner, said chamber having an inlet and an outlet, a vertically movable needle for controlling the chamber inlet, a float having an arm pivotally secured to said needle, a vertically movable member operatively connected to said arm to support the same, and heat responsive means for raising and lowering said last mentioned member to vary the burner oil level and maintain the surrounding atmosphere at a constant temperature.

5. In combination, a burner, a fuel supply connected for gravity feed thereto, a fuel control chamber in the connection for controlling the oil level in the burner, said chamber having an inlet and an outlet, a vertically movable needle for controlling the chamber inlet, a float having an arm pivotally secured to said needle, a vertically movable rod operatively connected to said arm to support said float, a wafer thermostat fixedly positioned above said rod, spring means for maintaining the end of said rod against said thermostat whereby expansion or contraction of said thermostat moves said rod vertically to vary the burner oil level and maintain the surrounding atmosphere at a constant temperature.

6. In combination, a burner, a fuel supply connected for gravity feed thereto, a fuel control chamber in the connection for controlling the oil level in the burner, said chamber having an inlet and an outlet, a vertically movable needle for controlling the chamber inlet, a float having an arm pivotally secured to said needle, a vertically movable rod operatively connected to said arm to support said float, a wafer thermostat fixedly positioned above said rod, spring means for maintaining the end of said rod against said thermostat whereby expansion or contraction of said thermostat moves said rod vertically to vary the burner oil level and maintain the surrounding atmosphere at a constant temperature, and manually adjustable means for varying the vertical position of said wafer thermostat to vary the normal vertical position of said arm and alter said oil level whereby to change the temperature at which the surrounding atmosphere will be maintained.

In witness of the foregoing we affix our signatures.

JACOB T. LANDGRAF.
